SEWING MACHINE

George A. Fleckenstein, Stratford, Conn., assignor
to The Singer Manufacturing Company, Eliza-
beth, N. J., a corporation of New Jersey

Application September 6, 1934, Serial No. 742,918

12 Claims. (Cl. 112—235)

This invention relates to improvements in sewing machines and has for its primary object to provide for efficiently advancing work past the stitch-forming mechanism of a sewing machine having a four-motion feed yieldingly opposed by a presser-device.

More specifically, the invention has for its object to minimize friction in the bearing or bearings of a presser-foot carrying bar shifted endwise incidentally to the action of a work-advancing feed mechanism operated at high speed.

With the above and other objects in view, the invention comprises the devices, combinations and arrangements of parts hereinafter described in connection with the accompanying drawing which illustrates several embodiments of the invention, from which the several features of the invention and the advantages attained thereby will be readily understood by those skilled in the art.

In the accompanying drawing, Fig. 1 is a front end elevation, partly in section, of a sewing machine containing one embodiment of the present invention. Fig. 2 is an enlarged sectional view of the carrying bracket of the thrust-absorbing roller, the section being taken substantially on the line 2—2 of Fig. 1. Fig. 3 is an enlarged bottom plan view of the roller-carrying bracket shown in Fig. 1 as secured upon the presser-bar bearing bushing, the presser-bar being shown in section. Fig. 4 is a fragmentary front end elevation of the bracket-arm head of a sewing machine containing a modified friction-reducing device for the presser-bar. Fig. 5 is a rear side elevation of the modification shown in Fig. 4. Figs. 6 and 7 represent front end and rear side views in elevation of another modification of the present improvement.

Referring to the drawing, a sewing machine containing the present improvement is illustrated as having a cloth-plate 1, provided with the usual throat-plate 2, and a bracket-arm overhanging the cloth-plate, which bracket-arm terminates at its free end in a hollow head 3.

Journalized for vertical reciprocation in the bracket-arm head 3 is a needle-bar 4, carrying at its lower end a needle 5 and connected by a link 6 to a crank-disk 7 carried by a rotary needle-reciprocating shaft 8. The needle 5 operates, in the formation of stitches, with suitable loop-taker mechanism (not shown) disposed below the cloth-plate.

The work to be stitched is intermittently advanced across the cloth-plate 1 by a feeding mechanism of the lower four-motion type and in-

cluding a feed-dog 9, carried by a feed-bar 10 and projected through suitable feed-slots in the throat-plate 2. Any suitable mechanism may be employed for imparting the usual rising and falling, and the work-advancing and return movements to the feed-dog.

Yieldingly opposed to the feed-dog 9 is a presser-foot 11 detachably secured to the lower end of a vertically disposed presser-bar 12 journaled for endwise movement in a fixed bearing bushing 13. The bushing 13 is suitably secured in an aperture in the lower wall of the bracket-arm head 3 to extend within said head and to depend therefrom a substantial distance. Preferably, the bushing 13 depends from the head 3 the maximum extent permitting the requisite vertical movement of the presser-foot 11, to thereby increase the effectiveness of said bearing in supporting the presser-bar against the side thrust thereof occasioned by the engagement of the presser-foot by the feed-dog during work-advancing movements of the latter at high speed operation.

At its upper end the presser-bar 12 slidably enters a capped bearing-bushing 14 adjustably threaded into the upper wall of the bracket-arm head 3 and held secured in adjusted position by a set-screw 15. The presser-bar 12 has a bore 16 preferably extending the major portion of the length of the bar and from the upper end thereof, to receive a coil spring 17 and an abutment rod 18. The rod 18 is interposed between the cap of the bushing 14 and the coil spring 17, whereby the presser-bar is yieldingly urged downwardly toward the work-support under an adjustable pressure.

Embracing the presser-bar is the usual lifter-sleeve 19, of which the upper end engages a collar 20 clamped upon the presser-bar and the lower end carries a laterally extending arm 21 engageable by the usual hand lifter-lever 22 pivotally mounted upon the bracket-arm head.

In the form of the improvement illustrated in Figs. 1 to 3 inclusive of the drawing, there is clamped, by a screw 23 upon the portion of the fixed bushing 14 below the head 3, a split collar 24 having depending spaced bracket-members 25 disposed at the rear side of the presser-bar 12. Mounted between the bracket-members 25, for rotation about an axis transverse to the line of feed, is a roller 26 journaled upon an eccentric portion 27 of a shouldered spindle or bolt 28 rotatably adjustable in suitable apertures provided in the bracket-members 25 and clamped in set position by a nut 29. The roller supporting spin-

dle 28 is preferably set so that, normally, the roller 26 is barely in contact with the rear face of the presser-bar 12, it being obvious of course that the roller may be adjusted relatively to the presser-bar by turning the spindle 28.

At slow speeds of operation of the sewing machine, the presser-bar spring 17 effectively acts to lower the presser-foot 11 upon the throat-plate 2, with the work-disengaging movement of the feed-dog 9 and before the feed-dog again engages the work in a succeeding work-advancing movement thereof. However, at higher speeds of operation of the machine, the friction between the presser-bar and its bearing or bearings is so materially increased by the thrust of the feed-dog in its action to advance the work, that the spring 17 cannot function to completely lower the presser-foot between consecutive work-disengaging and work-engaging movements of the feed-dog. In this connection, it is to be borne in mind that there are limits to the pressure which may be exerted, without detriment, by presser-bar springs and particularly with certain classes of work. However, the roller 26 constitutes anti-friction means absorbing excessive lateral thrusts imparted to the presser-bar, thereby relieving the presser-bar bearing from excessive friction.

In the modification of the improvement illustrated in Figs. 4 and 5 of the drawing, there is provided a bow-spring 30, of which the upper end engages the rear outer face of the bracket-arm head 3 above the lifter-arm 21 and the suitably rounded lower end engages the rear face of the presser-bar below the bearing bushing 13. The bow-spring 30 is adjustably tensioned by a screw 31 threaded into the head 3, whereby said spring yieldingly engages the presser-bar 12 with sufficient pressure and in a suitable direction to counteract excessive bearing-friction inducing thrusts of the feed-dog upon the presser-bar. The spring 30 is provided with a slot 32 affording clearance for movement of the hand lifter-lever 22 and the lifter-arm 21.

In another modification illustrated in Figs. 6 and 7 of the drawing a split collar 33 is clamped upon the portion of the bushing 13 below the head 3, said collar having a rearwardly extending and flat-sided ear 34. The ear 34 carries a fulcrum-pin 35 projecting from the opposite flat-sides of said ear in a direction transverse to the direction of feed. Pivotaly hung upon the opposite ends of said fulcrum pin to depend therefrom in parallel relation are a pair of spaced arms 36 carrying a spindle or bolt 37 upon which is journaled a roller 38 disposed between said arms 36. The spindle 37 preferably corresponds with the spindle 28 illustrated more particularly in Fig. 2 of the drawing, in that it likewise has an eccentric portion for adjustably supporting the roller 38 and is secured in set positions by a nut 39. Engaging the rearward faces of the arms 36, are the spaced members 40 of a forked bow-spring 41, of which the opposite end bears against the rearward face of the head 3. A screw 42 threaded into said head 3 serves to suitably tension the spring 41 to counteract the excessive friction-inducing tendency between the presser-bar and its bearings at high speeds of operation of the machine. It will be understood that the modification illustrated in Figs. 6 and 7 of the drawing constitutes a combination of the anti-friction thrust-absorbing means of Figs. 1 to 3 of the drawing and the yielding thrust-absorbing means of Figs. 4 and 5 of the drawing.

Having thus set forth the nature of the invention, what I claim herein is:—

1. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a presser-bar bearing, and thrust-absorbing means opposing lateral thrust of the presser-bar upon said bearing. 10

2. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a presser-bar bearing providing for endwise sliding movements of the presser-bar thereupon, and thrust-absorbing means opposing lateral thrust of the presser-bar upon the rear wall of said bearing in the 20 direction of feed.

3. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a presser-bar bearing, and anti-friction means opposing lateral thrust of the presser-bar upon said bearing. 25

4. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a presser-bar bearing, and yielding thrust-absorbing means opposing lateral thrust of the presser-bar upon said bearing. 35

5. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a presser-bar bearing providing for endwise sliding movements of the presser-bar thereupon, and thrust-absorbing means carried by said bearing opposing lateral thrust of the presser-bar upon said bearing. 45

6. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a presser-bar bearing providing for endwise sliding movements of the presser-bar thereupon, and means disposed for engagement with said presser-bar between said bearing and presser-foot and acting to oppose lateral thrust of the presser-bar upon said bearing. 55

7. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a presser-bar bearing providing for endwise sliding movements of the presser-bar thereupon, and a roller supported for bodily adjustment in a direction opposed to the direction of feed and into position for engagement by said presser-bar. 65

8. In a sewing machine, stitch-forming mechanism, a work-support, means for advancing work upon said work-support including a four-motion feed-dog, a presser-foot yieldingly opposed to 70

work-engaging movements of said feed-dog, a presser-foot carrying bar, a presser-bar bearing providing for endwise sliding movements of the presser-bar thereupon, anti-friction thrust-absorbing means, and spring means yieldingly urging said thrust-absorbing means into engagement with said presser-bar.

11. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a tubular bearing in which said presser-bar is journaled for endwise movement, a bracket carried by said bearing, and a thrust-absorbing roller journaled upon said bracket for engagement by said presser-bar to thereby oppose lateral thrust of the presser-bar upon said bearing. 5

12. In a sewing machine, stitch-forming mechanism, a work-support, means for advancing work upon said work-support including a four-motion feed-dog, a presser-foot yieldingly opposed to work-engaging movements of said feed-dog, a presser-foot carrying bar, a tubular bearing in which said presser-bar is journaled for endwise movement, a bracket carried by said bearing, a thrust-absorbing roller journaled upon said bracket for engagement by said presser-bar to thereby oppose lateral thrust of the presser-bar 10
